[57] CLAIM

The ornamental design for a combined portable power vacuum and blower, as shown and described.

DESCRIPTION

FIG. 1 is a top, front and left side perspective view of a combined portable power vacuum and blower showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a front elevational view thereof; and

FIG. 8 is a top, front and right side perspective view thereof.

The electric cord is shown broken away in FIGS. 1-5 for ease of illustration and is understood to represent indeterminate length.

FIG. 1

FIG. 2

FIG. 3FIG. 4FIG. 8
